(57) **CLAIM**

The ornamental design for a clothes dryer vent exhaust for a building exterior wall, as shown and described.

DESCRIPTION

FIG. 1 is a front perspective view of the present invention, showing the new design of the clothes dryer exhaust vent for a building exterior wall;

FIG. 2 is a back perspective view thereof;

FIG. 3 is a front elevational view thereof;

FIG. 4 is a back elevational view thereof;

FIG. 5 is a first side elevational view thereof;

FIG. 6 is a second side elevational view thereof;

FIG. 7 is a top plan view thereof; and,

FIG. 8 is a bottom plan view thereof.

The broken lines shown in the figures are for the purpose of illustrating portions of the clothes dryer exhaust for a building exterior wall and form no part of the claimed design.
